UNITED STATES PATENT OFFICE.

JOSEPH COMEAU, OF PROVIDENCE, RHODE ISLAND.

ATTACHMENT FOR LADDERS.

Application filed February 20, 1923. Serial No. 620,209.

To all whom it may concern:

Be it known that I, JOSEPH COMEAU, a citizen of the United States, residing at Providence, in the county of Providence and 5 State of Rhode Island, have invented certain new and useful Improvements in Attachments for Ladders, of which the following is a specification.

This invention relates to an attachment 10 designed more particularly to be applied to a ladder used by linemen in repairing telephone cable wires and the like, and has for its object to provide an attachment which may be readily applied to a ladder, the same 15 being provided with a pair of hook-shaped arms whereby the upper end of the ladder may be adapted to engage an aerial wire such as used in telephone service, and for other similar purposes, and to provide a 20 convenient support for the repair men in operating upon a cable.

A further object of the invention is to so form the members of my improved attachment that they may be detachably connected together whereby when not in use 25 the parts may be folded one upon the other into a convenient and compact bundle to be used as a regular part of a lineman's kit.

With these and other objects in view, the 30 invention consists of certain novel features of construction, as will be more fully described, and particularly pointed out in the appended claims.

In the accompanying drawings:

35 Figure 1 is a perspective view illustrating my improved device as applied to a ladder and as connecting the upper end of the ladder to a telephone wire.

Figure 2 is a detailed construction illustrating 40 my improved device as applied to the upper end of a ladder.

Figure 3 shows one of the sides of a ladder in section and a portion of one arm of my improved attachment as clamped to 45 the side of the ladder.

Figure 4 shows the suspended seat detached.

Figure 5 shows the tool tray.

It is found in practice by telephone wire 50 repair men, of advantage to provide a simple and practical ladder attachment whereby the upper end of the ladder may be connected to a cable supporting wire in such a way that the ladder cannot possibly be accidentally disconnected from the wires and at the

same time hang a sufficient distance from the wire so as not to interfere with the freedom of movement of the operator upon the wire; that is, the ladder should hang just far enough away from the wire so that a workman on the ladder will be within easy working reach of the wire to be operated upon so as to permit the workman to make the necessary repairs. In some cases, a seat may be provided for the support of the operator 60 when the work is long and tedious. The following is a detailed description of one construction by which these advantageous results may be accomplished:—

With reference to the drawings, 10 designates the two spaced-apart sides of a ladder employed by linemen, which sides are connected by the usual rounds 11. Near the upper end of the ladder, I have attached the horizontally-disposed arms 12. One end 70 of each arm is drilled to receive the ends 13 of the clamp bar 14 which ends are threaded to receive the thumb nuts 15 whereby when the nuts are set up the arm 12 is quickly and securely clamped to the side 75 of the ladder being preferably positioned just above one of the rounds 11 so that it is impossible for the arms to slide downwardly even though the clamp should become slightly loosened.

The outer end of each of these arms is 80 preferably formed slightly thinner than the clamp end thereof and is bent back upon itself as at 16 providing an elongated hook 85 with its end 17 turned slightly outwardly to permit engagement with the wire 18, and when this wire is engaged by the hooks of both arms the great length of the hook positively insures the ladder from becoming inadvertently disconnected from the wire so 90 as to insure the linemen against a fall by accidental disconnecting of the ladder from the wire.

In order to further support the outer or hooked end of the arm, I have provided a 100 stay rod 19 for each arm, the outer end of the rod being removably connected to the outer end of its arm 12 by means of a bolt 20 which passes through the arm and the rod and a nut 21 is threaded onto the free end 105 of the bolt to lock the rod to the arm. The upper end of this rod is designed to lie against the outside surface of the side of the ladder and is bound thereagainst by means of a clamp such as that shown in Figure 3, 110

at 14, the threaded ends 22 of this clamp being provided with clamp nuts 23 whereby this end is bound securely to the side of the ladder thus firmly supporting the outer end 5 of the arm against any weight which may be applied thereto.

In some instances when the job to be done by the linemen, requires considerable time, it has been found convenient to support the 10 ends of a seat 24 on the opposite arms as illustrated in dotted lines in Figure 2, whereby the workmen may be comfortable while repairing a wire, and in other cases the ends of a seat 31, as shown in Figure 4 may be 15 suspended from these arms as shown in Figures 1 and 2, to support the body of a workman a convenient working distance below the wire. To provide this suspending support for the seat, I have attached a chain 20 25 to each corner of the seat 31 and the free end of each chain is provided with a hook 32 to engage a corresponding hole 33 in its arm. I have also shown a tool carrying tray 26, see Figures 5 and 6, as supported at the 25 30 ends of the arms by brackets 27, each of which is provided with a hook 32 at its end to engage a pin 28 in the arm, the same being within easy reach of the workman and the tray being provided at either end with a downwardly turned lip 29 to catch over the sides of the brackets, the upturned ends 30 of which lock the tray in operative position on the brackets.

The members of my improved attachment 35 are preferably made of comparatively thin light stock by which construction an extremely strong and durable construction as will be noted is formed and each of these parts may be readily disconnected from the 40 side of the ladder and from each other whereby the members may be readily assembled in a bundle to be carried in a workman's kit.

My improved ladder attachment is 45 extremely simple and practical in construction and by its use a lineman may readily apply it to his ladder to support the ladder in exactly the right position so that he may readily operate upon a cable with perfect safety and when he has finished it may be 50 quickly detached from the ladder and compactly folded for easy transportation.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A ladder attachment comprising a pair of arms adapted to be removably clamped to the opposite side members of a ladder, the outer end of each arm having an elongated reverse bend forming a deep support engaging hook, and an angularly disposed brace bar connecting the outer end of each arm with its ladder side, said arms cooperating to provide a support for a cross seat. 70

2. A ladder attachment comprising a pair of arms adapted to be removably clamped to the opposite side members of a ladder, the outer end of each arm having an elongated reverse bend forming a deep support 75 engaging hook, an angularly disposed brace bar connecting the outer end of each arm with its ladder side, and a cross seat supported on said arms all of which members of the device are detachably connected to a ladder and detachably connected together whereby they may be folded into a compact bundle.

3. A ladder attachment comprising two hooked-shaped arms adapted to be clamped to the sides of a ladder, an angularly-disposed support for the outer end of each arm, and seat suspended from said arms. 85

4. A ladder attachment comprising a pair of hook-shaped arms adapted to be clamped to the sides of a ladder, an angularly-disposed support for the outer end of each arm, a seat suspended from and below the plane of said arms, and a tool carrying tray also supported from said arms. 90

5. A ladder attachment comprising a pair of arms having support engaging means adjacent their free ends, their opposite ends being adapted to be clamped to the sides of the ladder, an angularly-disposed support 100 for the outer end of each arm, and a seat suspended from said arms.

In testimony whereof I affix my signature.
JOSEPH COMEAU.
